1862. Design for A Clock, Bust and Inkstand.

By William A. Giles.

Patented April 3, 1866   Chicago, Ill.

W. A. Giles
Inventor

William A. Giles of Chicago Ill.,
 Letters Patent No. 33,923, Dated April 3rd 1866.
 Design for a Bust & Clock Case.

The schedule referred to in the Letters Patent and making part of the same

To whom it may concern:

Be it known that I, William A. Giles of Chicago in the County of Cook and State of Illinois have invented or produced a new and original design for a Bust, Clock and Inkstand combined and I do hereby declare that the following is a full and exact description thereof:

There is nothing peculiar about the base of this design. It may be made as in the drawing or in any other form substantially the same. In the centre of the base is a clock, the case of which is square or nearly so, with the ordinary circular face in the middle of the front side. On each side of this clock case, to the right and left is a small projection as shown in the drawing; one showing the month and the other the day of the month, by means of mechanism within the clock, and which it is not necessary here to describe.

Above and resting upon the clock case is a Bust of President Lincoln, with his face turned nearly to the front.

On each side of the base, or perhaps it would be better to say at each end is an inkstand.

Having thus described my design, what I claim as my invention or production and desire to secure by Letters Patent is.

'The design for a clock case, Bust and Inkstand combined substantially as shown and described.'

Witness,

George Rayton

Chas. A. Gregory.

W. A. Giles.
